US0D1086793S

(12) **United States Design Patent** (10) **Patent No.:** **US D1,086,793 S**
(45) **Date of Patent:** ** *Aug. 5, 2025

(54) **CONTAINER CAP**

(71) Applicant: **Joseph R. Stanek**, Orchard Park, NY
(US)

(72) Inventor: **Joseph R. Stanek**, Orchard Park, NY
(US)

(*) Notice: This patent is subject to a terminal disclaimer.

(**) Term: **15 Years**

(21) Appl. No.: **29/809,462**

(22) Filed: **Sep. 28, 2021**

(51) LOC (15) Cl. **07-02**

(52) U.S. Cl.
USPC **D7/391; D9/443**

(57) **CLAIM**

The ornamental design for a container cap as shown and described.

DESCRIPTION

FIG. 1 is a top front perspective view of a container cap showing my new design;

FIG. 2 is a bottom rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a cross section view thereof.

1 Claim, 7 Drawing Sheets
